UNITED STATES PATENT OFFICE

ARTHUR A. PANNIER, OF SALT LAKE CITY, UTAH

DESIGN FOR AN ANIMAL TAG

Application filed May 17, 1929. Serial No. 31,272. Term of patent 14 years.

To all whom it may concern:

Be it known that I, ARTHUR A. PANNIER, a citizen of the United States, and a resident of Salt Lake City, county of Salt Lake, and State of Utah, have invented a new, original, and ornamental Design for an Animal Tag, of which the following is a specification, reference being had to the accompanying drawing, forming part thereof.

In the drawing,

Fig. 1 represents a front elevation of an animal tag showing my new design; and Fig. 2, a top plan thereof.

The cross-lining indicates open spaces or perforations, and not a color.

I claim:

The ornamental design for an animal tag, as shown and described.

A. A. PANNIER.
